UNITED STATES PATENT OFFICE.

BENJAMIN V. ARNSTINE AND HARRY W. ARNSTINE, OF CLEVELAND, OHIO.

DESIGN FOR A SHOW-CASE.

SPECIFICATION forming part of Design No. 29,035, dated July 12, 1898.

Application filed March 26, 1898. Serial No. 675,327. Term of patent 3½ years.

To all whom it may concern:

Be it known that we, BENJAMIN V. ARNSTINE and HARRY W. ARNSTINE, citizens of the United States of America, and residents of 5 Cleveland, county of Cuyahoga, and State of Ohio, have invented a new and original Design for Show-Cases, of which the following is a specification.

In the accompanying drawing, forming part 10 of this specification, the figure is a perspective view of a sample show-case, showing our new design.

As shown in the drawing, the leading or material features of our design consist of a case, 15 pyramidal in form, comprising four glass panels A A, set in frames of flat corner-moldings. The four frames are made one-half the width at their top lines in proportion to their bot-

tom lines, and the four frames are joined on their slanting lines to form the pyramidal-shaped case. The top of the case is closed by a flat square panel B. The upper and lower corners of the case have the decorated portions C C.

Having described our invention, what we 25 claim, and desire to secure by Letters Patent, is—

The design for a show-case, as herein shown and described.

Signed by us, at Cleveland, Ohio, this 23d 30 day of March, 1898.

BENJAMIN V. ARNSTINE.

HARRY W. ARNSTINE.
